CLAIM

The ornamental design for an environmental waste water filtering system base, as shown and described.

DESCRIPTION

FIG. 1 is a top perspective view of an environmental waste water filtering system base;

FIG. 2 is a bottom perspective view of the environmental waste water filtering system base;

FIG. 3 is a front elevational view of the environmental waste water filtering system base;

FIG. 4 is a left elevational view of the environmental waste water filtering system base;

FIG. 5 is a bottom plan view of the environmental waste water filtering system base;

FIG. 6 is a top plan view of the environmental waste water filtering system base;

FIG. 7 is a front cutaway view of the environmental waste water filtering system base; and,

FIG. 8 is a left cutaway view of the environmental waste water filtering system base.

The back view is a mirror image of FIG. 3, and the right view is a mirror image of FIG. 4.

The broken lines shown in the figures illustrate environment that forms no part of the claimed design.
